(57) **CLAIM**

The ornamental design for a dip stick housing closure, as shown and described.

DESCRIPTION

FIG. 1 is a perspective view of our dip stick housing closure showing the environment of use;

FIG. 2 is an exploded front perspective of our dip stick housing closure in FIG. 1 in the open condition;

FIG. 3 is a front elevation of our dip stick housing closure in FIG. 1;

FIG. 4 is a rear elevation of our dip stick housing closure in FIG. 1;

FIG. 5 is a right side elevation of our dip stick housing closure in FIG. 1;

FIG. 6 is a left side elevation of our dip stick housing closure in FIG. 1;

FIG. 7 is a top plan view of our dip stick housing closure in FIG. 1;

FIG. 8 is a bottom plan view of our dip stick housing closure in FIG. 1;

FIG. 9 is a perspective view of our dip stick housing closure in the closed condition;

FIG. 10 is a front elevation of our dip stick housing closure in FIG. 9; the rear elevation is the mirror image of FIG. 10;

FIG. 11 is a right side elevation of the dip stick housing closure in FIG. 9; the left side elevation is the mirror image of FIG. 11;

FIG. 12 is a top plan view of the dip stick housing closure in FIG. 9;

FIG. 13 is a bottom plan view of our dip stick housing closure in FIG. 9; and,

FIG. 14 is a section view illustrating the closed condition of our dip stick housing closure.

The broken line showing in the drawings is included for the purpose of illustrating environment and forms no part of the claimed design for our dip stick housing closure in FIG. 9.

1 Claim, 12 Drawing Sheets
